UNITED STATES PATENT OFFICE.

HARVEY HUBBELL, OF BRIDGEPORT, CONNECTICUT.

SEPARABLE ATTACHMENT-PLUG.

No. 923,179.

Specification of Letters Patent.

Patented June 1, 1909.

Application filed October 30, 1908. Serial No. 460,239.

To all whom it may concern:

Be it known that I, HARVEY HUBBELL, a citizen of the United States, residing at Bridgeport, county of Fairfield, State of Connecticut, have invented a new and useful Separable Attachment-Plug, of which the following is a specification.

This invention relates to separable attachment plugs for use in electric circuits, and 10 has for its general objects to simplify and cheapen the construction and to greatly reduce the size of the plug.

It is one of the objects of the invention to provide an attachment plug cap which may be 15 made from any ordinary plastic composition as hard rubber, so called, but which shall be provided with an insulating heat-resisting disk to which the electrical connections are attached thus giving to the structure all the 20 advantages of hard rubber, so called, and making a durable and perfectly safe structure.

A further object of the invention is to provide means for connecting the cable to the 25 cap in such a manner as to prevent the end of the cable from fraying and preventing the end of the cable from being partly pulled out from the cap and loose ends of the covering threads escaping.

30 A further object of the invention is to provide an attachment plug base in which the usual intermediate part of porcelain within which the contacts engage may be dispensed with and the base shall be so constructed 35 that the engagement of the contacts will take place within the screw shell.

With these and other objects in view the invention consists in certain constructions and in certain parts, improvements and combinations which will be hereinafter described 40 and then specifically pointed out in the claim hereunto appended.

In the accompanying drawing forming a part of this specification, Figure 1 is a longitudinal section of my novel attachment plug complete; Fig. 2 a detail sectional view illustrating in connection with Fig. 1 my novel mode of attaching the cable to the cap; Fig. 3 an inverted plan view of the base with 45 the screw shell removed; Fig. 4 a plan view of the base of the screw shell removed; and Fig. 5 is a section on the line 5—5 in Fig. 1, looking in the direction of the arrows.

10 denotes the cap as a whole, 11 the base 50 as a whole and 12 the cable. The cap comprises upper and lower parts indicated re-

spectively by 13 and 14 and provided respectively with male and female threads by which they are secured together. Both of these parts may be molded from hard rubber, 60 so called.

15 denotes an internal recess in the cap into which the cable leads through a central hole 16 in part 13.

17 denotes the contact plates which are 65 secured in the recess and extend through slots 18 in the bottom part 14 of the cap.

An important feature of the present invention is that the electrical connections are attached to an insulating heat-resisting washer 70 indicated by 19. This washer may be made of mica, vulcanized fiber or any insulating material that will resist heat. This insulating washer lies at the bottom of recess 15. The bases of the contact plates, indicated by 75 20, are riveted or otherwise secured to the upper side of the washer and the plates themselves extend through slots in the washer in alinement with slots 18 in part 14.

21 denotes the binding screws which engage 80 the bases of the contact plates, and 22 the current wires which engage the binding screws in the usual manner.

Another important feature of the invention is the mode of connecting the cable to 85 the cap. 23 denotes a beveled recess in the under side of part 13 and surrounding the hole for the cable and 24 denotes a soft rubber ring which lies in this recess and clamps the end of the cable firmly when part 13 90 of the cap is screwed to place (see Figs. 2 and 1). In assembling, the cable is passed through part 13 of the cap and the ring, as clearly shown in Fig. 2, the loose threads at the end of the cable being below the ring. 95 When the parts are secured together by means of the screw threads, this soft rubber ring will be compressed between the binding screws, the bases of the contact plates, part 13 and the cable into a more or less triangular form in cross section; as shown in Fig. 1, and will grip the cable tightly, wholly preventing the loose threads at the end of the cable from being pulled through the cap; in other words, preventing the cable from being frayed above the cap. 100

Another and vitally important feature of the present invention is that the usual intermediate part of porcelain, lying wholly above the screw shell, within which the engagement of the contact plates with the contact springs is made, is dispensed with and 110

the engagement of the contact plates and contact springs is caused to take place within the screw shell. I thereby materially reduce the cost of construction and am enabled to make the attachment plug as a whole approximately a third shorter than has heretofore been possible. The base comprises an insulating block, preferably of porcelain, indicated by 25, a cupped screw shell indicated by 26, and an insulating disk 27 ordinarily made of vulcanized fiber to which the screw shell is secured. The upper end of the screw shell is shown as reduced slightly in diameter, as at 28, and said reduced portion is inclosed in an insulating ring 29 which rests upon the upper end of the threaded portion of the shell. The purpose of this ring is to prevent the hand from coming in contact with the live end of the shell in making and breaking the connection. The insulating block is provided near its lower end with a shoulder 30 which supports a cylindrical insulating lining indicated by 31 and over the outer edge of which the lower end of the screw shell is turned.

32 and 33 denote recesses in the insulating block which receive the contact springs indicated by 34 and 35. Contact spring 34 is secured to the screw shell by a rivet 36 which also secures the screw shell to insulating disk 27. The screw shell is secured to the insulating disk by additional rivets, one of which appears in dotted lines in Fig. 1. Con-

tact spring 35 is secured to the insulating block by means of a screw 37 which extends upward through the block and engages a nut 38. The screw shell and the insulating disk are provided with corresponding slots 39 through which the contact plates pass to engage the contact springs when the cap and base are connected. The passage of the current, starting from the left binding screw, is as follows: through the left contact plate and contact spring 35 to the center contact of a socket or receptacle, the return current being through the screw shell, contact spring 34 and the right contact plate to the right binding screw.

Having thus described my invention, I claim:

An attachment plug base comprising an insulating body, a screw shell inclosing the body, an insulating disk to which the screw shell is connected, said disk and the screw shell being provided with corresponding slots for the passage of contact plates and contact springs within the body and attached to the body and screw shell respectively, which are adapted to engage the contact plates.

In testimony whereof I affix my signature, in presence of two witnesses.

HARVEY HUBBELL.
